(57) **CLAIM**

The ornamental design for a lighting fixture having an illumination effect, as shown and described.

DESCRIPTION

This application contains subject matter which is related to the subject matter of concurrently filed U.S. Design patent application Ser. No. 29/612,018, entitled "Lighting Fixture" by Doyle Crosby; U.S. Design patent application Ser. No. 29/612,019, entitled "Recessed Lighting Fixture" by Doyle Crosby, which applications are hereby incorporated in their entirety herein by reference.

FIG. 1 is a left, front perspective view of a lighting fixture having an illumination effect, shown with illumination;

FIG. 2 is a front elevational view thereof;

FIG. 3 is a right, front perspective view thereof;

FIG. 4 is a top perspective view thereof;

FIG. 5 is a bottom perspective view thereof;

FIG. 6 is another left, front perspective view thereof, but shown without illumination;

FIG. 7 is a front elevational view thereof; and,

FIG. 8 is a right, front perspective view thereof.

FIGS. 1-6 show an illuminated effect that results from light being emitted between the outer rim and the inner curve bowl.

1 Claim, 8 Drawing Sheets
